ABSTRACT

A switching device which must be manually set for operation is electrically reset to a disabled condition during operation. The device has particular utility as an emergency override for an electrical interlock system because the switching device is automatically reset to prevent a subsequent switching operation, and, conversely, permits a one-time operation. To prevent the switching device from being used to permanently defeat the electrical interlock, the switching device has "trip-free" operation during the manual setting procedures.

CROSS-REFERENCES TO RELATED
APPLICATIONS

This application relates to subject matter disclosed and claimed in copending application Ser. No. 421,902 entitled "Manually Set Magnetic Relay" filed Dec. 5, 1973, copending application Ser. No. 421,903, entitled "Manually Set Magnetic Realy" filed Dec. 5, 1973, and copending application Ser. No. 421,904 entitled "Push Button" filed Dec. 5, 1973, all of the copending applications having the same assignee as the present application.

BACKGROUND OF THE INVENTION

The present invention relates to the field of switching devices and, more particularly, is related to a switching device such as a thermal or electromagnetic relay which must be manually set before each operation.

It is well known to provide electrical interlocks in systems to prevent operation unless specific conditions have been met. For example, as a safety measure in automobiles, the ignition system may be disabled until the driver and all of his passengers have fastened their seat belts. To implement such a system, an electrical interlock operated by sensors or switches sequentially set by the driver and passengers entering the car and fastening the belts may be provided in the ignition system of the automobile. Unless the belts are fastened after entry, the interlock disables the ignition system and the engine cannot be started.

It will be recognized that a failure of the electrical interlock system may completely disable the ignition system and prevent operation of the automobile. Such a situation may not only be frustrating to the driver and his passengers but also could prove to be a serious hazard particularly in an emergency situation in which the automobile must be moved.

To remedy the situation and eliminate the possible hazards posed by the electrical interlock it has been suggested that an override relay be provided to bypass the electrical interlock. The relay must be manually set before each override operation and disabled after operation. Naturally, to prevent repeated use of the relay, it is located in a position not readily accessible to the driver except in an emergency situation, and one likely location for the relay is the engine compartment.

It is, accordingly, a general object of the present invention to disclose a manually set switching device which automatically disables itself to limit its use to single-cycle or one-time operations.

SUMMARY OF THE INVENTION

The present invention resides in a manually set switching device for one-time operations. The switching device has particular utility as an override for an electrical interlock since the device must be manually set prior to each use and automatically resets and disables itself after a single overriding operation.

The switching device is designed to bypass an electrical interlock and, accordingly, the device is comprised of a first switch means for connection in a load circuit with the electrical interlock. The first switch means has a first condition overriding the interlock and a second condition permitting the interlock to operate. In the situation in which the first switch means is connected in parallel with the interlock, the first condition is a closed

condition bypassing the interlock and the second condition is an open condition permitting the interlock to operate in its normal fashion.

Manually operable enabling means sets the first switch means in the first condition overriding the interlock.

Preferably, the manually operable enabling means holds the first switch in the second condition until it is released to provide trip-free operation and to prevent the interlock from being permanently defeated by fastening manually operable means permanently in its actuated position.

Electrically operated disabling means cooperates with the enabling means to reset the switching device with the first switch means in the second condition permitting interlock operation. The electrically operated disabling means may be an electromagnetic force generator or a thermally operated actuator which latches the switching device in a disabled condition.

BRIEF DESCRIPTION OF THE DRAWINGS

FIG. 1 is an electrical diagram illustrating one embodiment of the manually set switching device of the present invention in a typical environment.

FIG. 2 is another electrical diagram similar to FIG. 1 and illustrates another embodiment of the manually set switching device in a slightly different environment.

FIG. 3 is a cross-sectional view of one embodiment of the manually set switching device prior to manual setting or actuation.

FIG. 4 is a cross-sectional view showing the manually set switching device of FIG. 3 during manual actuation.

FIG. 5 is a cross-sectional view similar to FIG. 4 following the manual actuation and during heating of the thermal element.

FIG. 6 is a cross-sectional view similar to FIG. 5 showing the switching device during cooling of the thermal element.

FIG. 7 is a cross-sectional view of another embodiment of the manually set switching device prior to manual actuation.

FIG. 8 is a cross-sectional view of the switching device in FIG. 7 during manual actuation.

FIG. 9 is a cross-sectional view showing the switching device in FIG. 8 during heating of the thermal element subsequent to manual actuation.

FIG. 10 is a cross-sectional view showing the switching device in FIG. 9 during cooling of the thermal element.

FIG. 11 is a perspective view of another embodiment of the manually set switching device having an electrically energized thermal actuator for resetting the device.

FIGS. 11a and 11b is a cross section of an ambient compensation assembly shown at two different ambient temperatures.

FIG. 12 is a cross-sectional view of the switching device in FIG. 11 showing the load contacts open and latched prior to manual setting or actuation and FIG. 13 is a corresponding cross-sectional view showing the heater contacts at the same time.

FIG. 14 is a cross-sectional view of the device in FIG. 11 showing the load contacts during manual actuation and FIG. 15 is a corresponding cross-sectional view showing the heater contacts at the same time.

FIG. 16 is a cross-sectional view of the device in FIG. 11 showing the load contacts closed following manual

actuation and FIG. 17 is a corresponding cross-sectional view showing the heater contacts at the same time.

FIG. 18 is a cross-sectional view of the device in FIG. 11 showing the load contacts closed during cyclic heating and cooling of the thermal element and FIG. 19 is a corresponding cross-sectional view showing the heater contacts at one instant during the same period.

FIG. 20 is a perspective view of still another embodiment of the switching device resembling that in FIG. 11 but utilizing an electromagnetic solenoid in place of the heated thermal element.

DESCRIPTION OF THE PREFERRED EMBODIMENTS

FIG. 1 is an electrical diagram showing schematically one embodiment of the manually set switching device in the starting circuitry of an automobile having an electrical ignition interlock. The interlock normally prevents energization of the electrical starter motor unless the seat belts in the automobile have been properly fastened in each of the occupied seats. It should be understood, however, that the switching device of the present invention may be employed in other environments to override and interlock or perform other similar functions to which its operation is suited.

The illustrated embodiment of the manually set switching device, generally designated 10, is connected serially in the electrical starting circuit between the ignition switch 12 and the starter solenoid 14 on the starter motor (not shown). A starter switch 16 and the coil 18 of the starter relay 20 are also connected in series with the load switch 22 within the switching device 10. The ignition switch 12 is, of course, connected to one of the battery terminals, the B+ terminal being illustrated, and the starter relay 20 and starter solenoid 14 are connected to the ground terminal through the frame of the automobile. The ignition switch 12 and the starting switch 16 are generally incorporated in a single housing and are closed sequentially by turning the ignition key through several index positions. The ignition switch 12 is closed first to energize the electrical system of the car and the starting switch 16 is closed last to pull the starter relay 20 in and energize the starter solenoid 14 and starter motor. Usually the last index position is spring-loaded so that the starting switch 16 automatically opens upon release of the key.

The load switch 22 of the switching device 10 is connected in parallel with the switch 24 of the interlock relay 26 forming part of the seat-belt interlock system. The system also includes a logic module 28 for energizing the relay 26 and completing the starting circuitry of the automobile when certain conditions have been met. The logic module 28 receives signals from sensing switches indicating which seats of the automobile are occupied and which seat belts have been fastened. If the seat belts are first occupied and then the respective seat belts are fastened in that order, a "go" signal normally issues from the module to actuate the coil of the interlock 26 and close the relay switch 24. If the logic module detects an unfastened seat belt in an occupied seat or if the sensing switches are not actuated in the proper order, indicating for example a permanently buckled seat belt, the interlock relay 26 is not energized and the starting circuit remains open.

If the logic module 28 is faulty and inoperative, the interlock contacts may not close and starting of the au-

tomobile cannot take place in its intended fashion. A faulty interlock may be frustrating and dangerous as well if the automobile must be moved in an emergency situation. In such case the manually actuated switching device of the present invention is employed to bypass the interlock relay 26.

The manually set switching device 10 in FIG. 1 is basically a manually set thermal relay in the starting circuitry and overrides the electrical interlock in a one-time or single-cycle operation. The device 10 is comprised of the load switch 22 previously described and a manually actuated switch 32 serially connected with the heater coil 34 of a thermal actuator.

The load switch 22 is normally open and, therefore, the logic module 28 and interlock relay 26 are enabled to perform the safety interlock operation for which they are intended. When the interlock system is inoperative and the automobile must be started in the absence of a go signal from the interlock logic module 28, the load switch 22 is closed and the interlock is disabled or bypassed. Closing of the load switch 22 is accomplished manually. The switch 32 is also closed manually to permit the heater 34 to be energized as soon as the ignition switch 12 is turned on. The thermal actuator is connected to both of the switches 22 and 32 so that de-energization of the actuator after the ignition switch 12 is opened leaves the two switches 22 and 32 in the open condition.

It is thus apparent that the switching device 10 must be manually actuated prior to an override operation in order to close the switch 22. The thermal actuator operated by the heater 34 resets the switches 22 and 32 in the condition when they can be opened after ignition switch 12 is de-energized so that a subsequent starting operation cannot be performed unless the interlock relay 26 is operable or switching device 10 is again manually set to enable the load switch 22.

FIG. 2 discloses an alternate manually actuated switching device, generally designated 40, connected in parallel with the interlock relay 26 in a starting circuit. The elements in FIG. 1 duplicated in FIG. 2 bear the same reference numerals. It will be noted that the starting circuit is slightly different from that shown in FIG. 1 due to the elimination of the starting relay which energized the starter solenoid 14. In FIG. 2 the solenoid 14 is energized directly through the load switch 22 or the interlock relay 26 when the ignition switch 12 and starter switch 16 are closed.

The switch 32 in the device 40 is manually actuated or moved to the closed position to enable the device 40 and disable or override the interlock relay 26 in the same manner as that described in connection with FIG. 1. However, the switch 32 is serially connected with an electrically energized actuator taking the form of an electromagnetic force generator or solenoid having a coil 42. The solenoid is mechanically connected with the load switch 22 to move the switch between open and closed positions. With the ignition switch 12 and the manually actuated switch 32 closed, the switching device 40 is enabled and the coil 42 of the solenoid is electrically energized. When the ignition switch 12 is opened to shut off the engine, the solenoid is de-energized and leaves the switches 22 and 32 open. The switching device 40 is, therefore, disabled and the interlock relay 26 is enabled.

It should be understood that the switching devices 10 and 40 are not limited in application to the specific

starting circuits shown in FIGS. 1 and 2 respectively, but, may be used interchangeable in the two starting circuits or in other systems employing an electrical interlock.

In the following descriptions of the different embodiments of the switching device, reference numerals utilized in the electrical diagrams of FIGS. 1 and 2 will be used to identify the corresponding components in the device.

FIGS. 3-6 illustrate one embodiment of the switching device, generally designated 50, with the components in different positions assumed sequentially in a single and complete operating cycle.

In FIG. 3 the switching device 50 is shown prior to the manual actuation or setting which initiates an interlock overriding operation. The switching device corresponds in electrical structure to the switching device 10 shown in FIG. 1. The load switch 22 is formed by two cantilevered, resilient and parallel clapper arms 52 and 54 having mating electrical contacts adjacent their free ends. The arm 52 carries an extension which is shown resting upon a slide assembly 56 supported in the housing 58 for sliding movement to the left and right in FIG. 3. A spring 60 at one end of the assembly 56 biases the assembly into contact with a manually depressible plunger 62 extending through a return spring 64 and the housing 58.

The manually actuated switch 32 is formed by contacts mounted respectively on the free ends of a cantilevered bimetallic arm 66 and a cantilevered clapper arm 68. The free end of the arm 68 rests on the slide assembly 56 at the edge of a cutout provided for the arm and its contact. The heater 34 is formed by a resistive wire wrapped around and electrically insulated from the bimetallic arm 66 and the arm is constructed in such a manner that as its temperature is increased by the heater 34, the free end of the arm flexes downwardly and away from the slide assembly 56. Conversely, upon cooling the arm flexes back toward the slide assembly and assumes the position illustrated at room temperature.

FIG. 4 illustrates the switching device 50 during manual actuation. The plunger 62 is manually depressed and causes the slide assembly 56 to shift to the right as illustrated in opposition to the biasing force of the spring 60. As the edge of the cutout on which the clapper arm 68 rests moves away from the free end of the arm 68, the arm flexes downwardly toward the bimetallic arm 66 and closes the contacts of the switch 32. In the course of the displacement of slide assembly 56, a depending tang 70 on the assembly first encounters a camming surface on a stop 72 attached to the housing 58. The camming surface lifts or flexes the cantilevered end of the slide assembly over the stop 72 and at the same time lifts a latch 74 on the slide assembly over the upwardly projecting tang 76 at the cantilevered end of the bimetallic arm 66. Also, the resilient extension of the clapper arm 52 slides onto the plunger 62 and thus holds the load switch 22 in the open condition for "trip-free" operation of the switching device. With trip-free operation, the electrical interlock is not permanently defeated by jamming the plunger 62 in the depressed position.

FIG. 5 shows the switching device 50 after the plunger 62 has been released and has been moved out of contact with the slide assembly 56 by the return spring 64. The resilient extension of clapper arm 52 is

no longer supported by the plunger 62 or the slide assembly 56 and, hence, the load switch 22 closes. The clapper arms 52 and 54 connected in parallel with the electrical interlock relay are, therefore, closed and disable or bypass the relay.

As shown in FIG. 5 the slide assembly 56 without the restraint of the plunger 62 shifts to the left until the latch 74 and the tang 76 engage one another. The displacement of the slide assembly 56 is not sufficient to open the switch 32 and, therefore, when the ignition switch 12 in FIG. 1 is closed, the heater 34 receives power and raises the temperature of the bimetallic arm 66. The free end of the arm 66 deflects downwardly until it assumes the phantom position illustrated and the latch 74 and tang 76 disengage. At that time the slide assembly 56 shifts a further increment to the left until the tang 70 hits the stop 72. Continued heating of the bimetallic arm 66 causes further deflection until the switch 32 opens.

FIG. 6 illustrates the switching device 50 after the switch 32 has been opened and during normal cycling of alternate heating and cooling as switch 32 opens and closes. The downwardly projecting tang 70 of the slide assembly 56 is in abutment with the stop 72. This condition will be maintained as long as switch 12 is maintained closed. When ignition switch 12 is opened bimetallic arm 66 will cool down and move in an upward direction. It will be observed that the latch 74 has a surface which is engaged by the tank 76 on the bimetallic arm as shown. Further cooling of the arm 66, therefore, moves the tang 76 upwardly from the position shown in FIG. 6 and lifts the end of the slide assembly 56 upwardly with it so that the tang 70 is lifted over the stop 72. The return spring 60 then urges the slide assembly 56 to the left into engagement with the plunger 62 and, at the same time, the extension of clapper arm 52 is lifted upwardly by the assembly to open the load switch 22. At this point the components of the switching device 50 are reset in the initial positions shown in FIG. 4 and, as a consequence subsequent attempts to start the engine of the car will be inhibited by the disabled switching device unless the mechanically actuated plunger 62 is again depressed or the electrical interlock is properly operated.

FIGS. 7-10 show a switching device, generally designated 80, which is an alternate construction of the switching device 50 shown in FIGS. 3-6 and since the device 80 shares many of the components of the device 50, corresponding parts are identified by the same reference numerals. The switching device 80 is, for the most part, identical to the switching device 50 except that the manually actuated switch 32 has been eliminated and the clapper arm 68 is replaced by a single conductor 82 permanently connected with the heater 34. The device 80 is connected serially in the starting circuit of an automobile in the same manner as the switching devices 10, 40 or 50 as shown in FIGS. 1, 2 or 3 respectively. Accordingly, the load switch 22 is connected in parallel with the electrical interlock and the circuit including the heater 34 is energized through the ignition switch of the automobile. Whenever the ignition switch is on, the heater 34 is operative.

In FIG. 7 the device 80 is shown prior to manual actuation of the plunger 62. When the plunger is depressed, the cam surface on the stop 72 lifts the latch 74 over the upwardly projecting tang 76 on the bimetallic arm 66 to the position shown in FIG. 8. The load

switch 22 is held open to provide trip-free operation of the switching device as described above until the plunger 62 is released as shown in FIG. 9. Without support, therefore, the extension of the clapper arm 52 falls into the gap between the plunger 62 and the slide assembly 56 and the load switch 22 closes. Starting of the automobile engine may then take place.

As soon as the ignition switch is closed, the heater 34 is energized and the bimetallic arm 66 flexes downwardly until the tang 76 is disengaged from the latch 74 at the position illustrated in FIG. 9 in phantom. Slide assembly 56 then shifts to the left until the tang 70 hits the stop 72.

Continued heating and the downward flexing of the bimetallic element 66 while the ignition switch is closed eventually reach an equilibrium condition. When the ignition switch is finally opened to shut the engine off, cooling of the arm 66 brings the upwardly projecting tang 76 back into engagement with a camming surface on the latch 74 as shown in FIG. 10 and then lifts the tang 70 over the stop 72. The return spring 60 shifts the slide assembly 56 to the left as shown in FIG. 10 and the components of the switching device assume the position shown in FIG. 7 with the extension of the clapper arm 52 holding the contacts of load switch 22 open to disable the switching device 80 until it is again manually set.

It will be observed that the switching device 80 provides a minimal period, for example 30 seconds, after the ignition switch is opened to again start or attempt to start the automobile engine independently of the electrical interlock. The exact length of the period depends upon the cooling characteristics of the bimetallic arm, the B+ voltage applied to the heater, and the temperature reached by the heater 34. To a greater extent the switching device 50 shown in FIGS. 3-6 provides a similar but more controlled period as it is adjusted to provide cyclic heating and cooling of the bimetallic arm 66; so that the temperature reached by the bimetallic arm and hence the duration of the period is controlled by the cycling of the heater when the ignition switch is closed.

FIG. 11 illustrates another embodiment of the switching device of the present invention taking the form of a thermal relay which must be manually set prior to each override operation and which automatically resets itself in a disabled condition following an override operation. Like the switching devices 50 and 80 described above, the switching device in FIG. 11, generally designated 90, provides a limited period following ignition turnoff within which engine starting can be attempted without manually setting the device.

The switching device 90 has the same electrical construction as that illustrated in the switching device 10 of FIG. 1. The load switch 22 completes the starting circuit and the mechanically actuated switch 32 is utilized to cyclically energize the heater 34.

All the components of the switching device 90 are mounted on a molded insulating base 92 and may be enclosed within a suitable protective cover attached to the base. The load switch 22 is formed by a pair of cantilevered and flexibly resilient clapper arms 94 and 96 positioned in overlying and confronting relationship. The free ends of the arms 94 and 96 include mating electrical contacts 98 and 100 respectively and the mounted ends of the clapper arms 94 and 96 are riveted to platforms on the base 92 by means of terminal

posts 102 and 104 respectively shown most clearly in FIG. 12. The lower ends of the terminal posts attach to the respective connecting pins 106 and 108.

The manually actuated switch 32 for controlling the heater 34 has basically the same construction as the load switch 22 and includes overlying and confronting clapper arms 114 and 116 having mating contacts 118 and 120 respectively. The clapper arms 114 and 116 are resilient and are mounted in cantilever fashion on the base 92 by terminal posts 122 and 124 respectively as shown in FIG. 13. A connecting pin 126 is fastened to the lower end of the terminal post 122. The terminal pin 124 is electrically connected to the heater 34.

Mounted on the base 92 adjacent the free ends of the clapper arms 94, 96, 114 and 116 is a latch assembly 130. The latch assembly is pivotally mounted in the base 92 on a fulcrum 132 and is biased counterclockwise about the fulcrum as viewed in FIGS. 12 and 13 by means of a leaf spring 134. The latch assembly includes two latches 140 and 142 which rock with assembly 130 about the fulcrum 132. The latch 140 has a notched upper portion shown most clearly in FIG. 12 which mates with the free end of the cantilevered clapper arm 96 in the unlatched position. In the position illustrated in FIG. 12 the clapper arm 96 rests on top of the latch 140 and the clapper arm 94 extends laterally adjacent the latch with the contacts 98 and 100 in spaced relationship. Load switch 22 is therefore, open.

The latch 142 shown in FIG. 13 cooperates with the free end of the clapper arm 116 to hold the switch 32 open while the lower clapper arm 114 extends laterally adjacent to the latch. A stop 144 shown most clearly in FIG. 11 projecting laterally from the latch 142 overlies the free end of the arm 114 to limit the upward motion of the arm.

FIG. 11 illustrates a manually operated electrically insulating plunger 150 of the switching device 90 slidably mounted in the slots of upright guide posts 152 and 154. The guide posts may be integrally formed in the insulating base 92 along with the platforms on which the cantilevered clapper arms 94, 96, 114 and 116 are mounted. The guide posts 152 and 154 position the manually actuated plunger 150 so that it engages one end of the latch assembly 130 when the plunger is depressed. Depressing the plunger causes the latches 140 and 142 to be pivoted about the fulcrum 132 away from the free ends of the clapper arms in opposition to the leaf spring 134. A plunger return spring 158 shown in FIG. 12 attaches to the upper portion of the plunger 150 and normally holds the plunger in the position illustrated out of contact with the latch assembly 130. When the plunger 150 is manually depressed either directly or by intervening elements such as a push button in a cover enclosing the thermal relay, the return spring 158 flexes and the lower portion of the plunger 150 engages the latch assembly 130 as well as the extension at the free end of the clapper arm 94.

Interposed between the two pair of parallel clapper arms 94, 96 and 114, 116 in FIG. 11 is a thermal actuator including the heater 34 and a bimetallic arm 160 riveted in cantilever fashion to a platform of the insulating base 92 by means of a terminal post 162. A connecting pin (not visible) similar to the connecting pins 106, 108 in FIG. 12 is connected to the lower end of the terminal post 162.

Fixedly attached to the free end of the bimetallic arm 160 is a transverse operating rod 164 which has oppo-

site ends extending respectively between the clapper arms 94, 96 as shown in FIG. 12 and the clapper arms 114, 116 as shown in FIG. 13. Rod 164 is either of insulating material or is insulated relative to the clapper arms. Raising the temperature of the arm 160 by means of the heater 34 causes the operating rod 164 to lift the clapper arms 96 and 116 above the latches 140 and 142 and allows the latch assembly 130 to move the latches under the respective arms. Cooling of the bimetallic arm 160 when the heater 34 is turned off lowers the free end of the arm and the operating rod 164 and depresses the lower clapper arms 94 and 114.

FIGS. 12-19 illustrate the sequence of positions assumed by the switching device 90 in a complete operating cycle. FIGS. 12, 14, 16 and 18 illustrate the clapper arms and contacts of the load switch 22 while FIGS. 13, 15, 17 and 19 illustrate the respective positions of the clapper arms and contacts of the manually actuated heater switch 32 at the same times.

FIGS. 12 and 13 illustrate the condition of the switching device 90 in the disabled condition with the ignition switch of the automobile turned off. The thermal actuator formed by the heater 34 and the bimetallic arm 160 in FIG. 11 is cool and, thus, the operating rod 164 is in its lowermost position. In FIG. 12 the lower clapper arm 94 is held down by the operating rod 164 and the upper clapper arm 96 is resting in its latched position on top of the latch 140 so that the contacts 98 and 100 are separated. The load switch 22 is, therefore, open. The leaf spring 134 holds the latch assembly in the position illustrated.

In FIG. 13 the lower clapper arm 114 is held down by the operating rod 164 and the upper clapper arm 116 is resting on top of the latch 142 so that the contacts 118 and 120 are separated. The heater switch 32 is, therefore, open.

To initiate overriding of the electrical interlock which would be connected in parallel with the load switch 22, the manually actuated plunger 150 is depressed and tilts the latch assembly 130 to the position shown in FIGS. 14 and 15. In FIG. 14 the latch 140 pivots clockwise about the fulcrum 132 and the upper clapper arm 96 drops downwardly into the lower notch on the latch as illustrated. At the same time an extension on the lower clapper arm 94 is engaged by the plunger 150 so that the arm 94 is depressed below the position established by the operating rod 164 and the load contacts 98 and 100 are held open for trip-free operation. Trip-free operation is desired to prevent the plunger 150 from being permanently jammed in the depressed condition to thereby permanently defeat the electrical interlock.

In FIG. 15 the heater switch 32 is shown at the same time with the free end of the upper clapper arm 116 out of the latched condition on top of the latch 140 and in contact with the lower clapper arm 114 through the contacts 118 and 120. The heater circuit within the switching device 90 is thus closed.

FIGS. 16 and 17 illustrate the load switch 22 and heater switch 32 immediately after the manually operated plunger 150 is released and returned to its uppermost position by the return spring 158 shown in FIG. 12. The load contacts 98 and 100 are closed since the lower clapper arm 94 has flexed resiliently upwardly into contact with the upper clapper arm in the notch of the latch 140. The latch assembly 130 when released by the plunger 150, rotates counter-clockwise in FIGS. 16

and 17 until the upper clapper arms 96 and 116 limit further rotation as illustrated.

At this point in the override operation the ignition switch of the automobile is turned on and the engine is started through the closed load switch 22 which bypasses the electrical interlock. At the same time the heater 34 is energized and the free end of the bimetallic arm 160 flexes upwardly away from the base 92. The operating rod 164 fixed to the arm 160 moves upwardly with the arm and carries with it the upper clapper arms 96 and 116 until both of the upper clapper arms are above the latches 140 and 142 as illustrated in FIGS. 18 and 19. The lower clapper arms 94 and 114 being resiliently biased upwardly tend to follow the upper arms 96 and 116 respectively as they are lifted by the operating rod 164. Both of the switches 22 and 32 remain closed initially; however, as the clapper arm 116 moves above the latch 142, the clapper arm 114 engages the limit stop 144. Since the heater 34 is still increasing the temperature of the bimetallic arm 160, the operating rod 164 continues to lift the upper clapper arm 116 until contacts 118 and 120 are broken as illustrated in FIG. 19. The bimetallic arm 160 then cools down and the operating rod 164 lowers clapper arm 116 until the contacts 118 and 120 close and the heating cycle is repeated. As long as the ignition switch of the automobile is closed, the cyclic heating and cooling of the bimetallic arm 160 continues and contact between the clapper arms 114 and 116 is made and broken. At the same time clapper arms 94 and 96 oscillate up and down together and the arm 96 remains above the latch 140. The load switch 22, therefore, remains closed and the automobile engine can be started as often as required.

When the ignition switch is finally opened to stop the automobile engine, current through the heater 34 is terminated, the bimetallic arm 160 cools to ambient temperature and the operating rod 164 returns to the position illustrated in FIGS. 12 and 13. The upper class arms 96 and 116 move into the latched positions on top of the latches 140 and 142 while the operating rod 164 depresses the lower clapper arms 94 and 114 and opens the contacts forming the switches 22 and 32. With the heater switch 32 open, subsequent energization of the relay through the ignition switch of the automobile has no effect and, therefore, the switching device 90 is disabled with the load switch 22 open to permit the electrical interlock to perform its intended function.

It will be observed that the cooling time of the bimetallic arm 160 provides a brief period, for example 30 seconds to 1 minute, after the ignition switch is turned off within which the engine can be restarted without having to manually reset the switching device 90. This interval is advantageous since it allows the engine to be restarted after a momentary or possibly inadvertent shutting off of the engine.

In the several thermal switches described above it may be desirable to provide ambient compensation for the bimetallic member, for example in order to obtain more consistent timing for resetting. An exemplary structure is shown in FIGS. 11a and 11b in which the bimetallic arm 160 of FIG. 11 is mounted on another bimetallic arm 161 having its high and low coefficient of expansion layers reversed relative to arm 160. Arms 160, 161 are joined by a relatively inflexible member 163. It will be noted that there is a distance *d* between rod 164 and base 92 which does not change from a first

ambient temperature (FIG. 11a) and a second higher ambient temperature (FIG. 11b) since the deflection of bimetallic arm 161 offsets the deflection of bimetallic arm 160.

FIG. 20 illustrates still another embodiment of a switching device, generally designated 170. The device 170 is constructed in a manner similar to the device 90 and hence corresponding elements bear corresponding reference numerals. The principal distinction between the devices 90 and 170 is that an electromagnetic force generator or actuator taking the form of a solenoid 172 replaces the thermal actuator formed by the bimetallic arm 160 and heater 134 in FIG. 11. The electrical diagram of the switching device 170, accordingly, corresponds to the device 40 shown in FIG. 2.

The solenoid 172 includes the coil 42 illustrated electrically in FIG. 2 and a U-shaped ferromagnetic support bracket 174 about which the coil 42 is wound. The bracket 174 is riveted at one end to the insulating base 92 by a terminal post 176 so that the opposite end of the bracket extends in cantilever fashion over the base 92. In addition, a clapper 178 is sandwiched between the base 92 and the bracket 174 at the terminal post 176 and extends in cantilever fashion relative to the base 92 and under the coil 42 so that in its unflexed condition a small gap exists between the free end of the clapper and the closely adjacent free end of the bracket 174. One lead (not shown) from the coil 42 is connected to a terminal 176 which has a connecting pin similar to the pins 106 and 108, and the other lead (not shown) from the coil leads to the terminal post 124. As a consequence, the switch 32 controls the energization and de-energization of the solenoid when the ignition switch 12 in FIG. 2 is turned on.

Extending transversely across the free end of the clapper 178 is an insulating or insulated operating rod 180. The operating rod 180 extends underneath both sets of parallel upper arms 94, 96 and 114, 116 and lifts the upper clapper arms 96 and 116 above the latches 140 and 142 respectively when the solenoid is energized. Energization of the solenoid, of course, cannot take place until the switch 32 is closed and this occurs when the manually actuated plunger 150 trips the latches 140 and 142 to allow the free ends of the clapper arms 114 and 116 to make electrical contact. Although desirable, it is not essential to have the clapper arms 94 and 96 make electrical contact when the latch 140 is released since the energizing of the solenoid 172 is certain to pull the free ends of the clapper arms 94 and 96 into contact as the arm 96 is lifted above the latch 140.

Release of the clapper arms from the latched position is otherwise identical in operation to that described in connection with FIGS. 12-17 including the trip-free operation produced by the engagement of the manually actuated plunger 150 and clapper arm 94. When the solenoid 172 is energized and has lifted the clapper arms above latches 140 and 142, no cycling operation equivalent to that described in connection with FIG. 19 takes place so that the solenoid 172 remains energized as long as the ignition switch 12 is closed. When the ignition switch opens, the upper clapper arms 94 and 116 are left in the latched condition and the entire switching device 170 is disabled until it is again manually set for an override operation.

While the present invention has been described in several preferred forms, it should be understood that

still other modifications and substitutions to the specific structures shown can be had without departing from the spirit of the present invention. For example, latch assembly 130 and the cooperating manually operated plunger may take forms other than that specifically illustrated as long as the latch 142 performs the latching function upon the switch 32 and disables the switching device when electrical power from the ignition switch is removed from the device. The load switch 22 formed by the clapper arms 94 and 96 need not necessarily be operated between a latched and unlatched condition provided that the arms acquire a normally open condition when the actuator, that is either the thermal actuator illustrated in the device 90 or the electromagnetic actuator illustrated in the device 170, is de-energized. In such case the actuator pulls the clapper arms 94 and 96 closed when the actuator is energized through the switch 32. Accordingly, the switching device of the present invention has been described in several different embodiments by way of illustration rather than limitation.

We claim:

1. A manually set switching device comprising: first switch means having an enabling switch condition and an overriding switch condition and operatively connectible to a load circuit; electrically energized force generating means operatively connected to the first switch means for moving the first switching means between the two switch conditions;

second switch means having enabling and disabling switch conditions and coupled with the electrically operated force generating means to control the energization and deenergization of the force generating means;

latch means operatively engagable with the second switch means for holding the second switch means in the disabling switch condition upon deenergization of the force generating means; and manually operable actuator means for disengaging the second switch means from the latch means.

2. A manually set switching device as in claim 1 wherein:

the force generating means is also operatively connected with the second switch means for moving the second switch means into the disabling switch condition on the latching means.

3. A manually set switching device as in claim 1 wherein:

the latching means is also operatively engagable with the first switch means for holding the first switch means in the enabling switch condition upon deenergization of the force means.

4. A manually set switching device for bypassing an electrical interlock in a one-time operation comprising: first switch means having an enabling switch condition and an overriding switch condition and operatively connectible to a load circuit in parallel with an electrical interlock to correspondingly enable or override the interlock; electrically energized force generating means operatively connected to the first switch means for moving the first switching means between the two switch conditions;

second switch means having enabling and disabling switch conditions and coupled with the electrically operated force generating means to control the en-

ergization and deenergization of the force generating means;
latch means operatively engagable with the second switch means for holding the second switch means in the disabling switch condition upon de- 5 energization of the force generating means; and manually operable actuator means for disengaging the second switch means from the latch means.

5. A manually set switching device as in claim 4 wherein:

the force generating means is also operatively connected with the second switch means for moving the second switch means into the disabling switch condition on the latching means.

6. A manually set switching device as defined in claim 4 wherein:

the electrically energized force generating means comprises an electrically heated thermal actuator.

7. A manually set switching device as in claim 6 wherein the thermal actuator comprises an electrical 20 heater and a bimetallic thermal element adjacent the heater.

8. A manually set switching device as in claim 6 wherein:

the force generating means is also operatively connected to the second switch means to move the second switch means onto the latching means.

9. A manually set switching device as in claim 4 wherein:

the latching means is also operatively engagable with the first switch means for holding the first switch means in the enabling switch condition upon de- 30 energization of the force generating means.

10. A manually set switching device as defined in claim 4 wherein:

the electrically energized force generating means comprises an electromagnetic force generator having a coil.

11. A manually enabled relay comprising:

a first pair of cantilevered clapper arms positioned with the free ends of the arms in confronting relationship and forming a first switch;

a second pair of cantilevered clapper arms positioned with the free ends of the arms in confronting relationship and forming a second switch;

a movable latch engagable with the free end on one arm of at least one of the pairs to hold the arms of the pair apart;

an electrically energized actuator means connected with the arms of each pair to move the arms of the respective pairs in and out of contact and to move the free end of the one arm of at least one of the pairs onto the movable latch; and

a manually operated actuator means engagable with the movable latch for unlatching the free end of the one arm.

12. A manually enabled relay as in claim 11 wherein the movable latch is engagable with the free end of the one arm of each of the first and second pairs.

13. A manually enabled relay as in claim 11 wherein:

the one clapper arm of the first pair is engaged by the movable latch in a latched position of the arm the electrically energized actuator means and the clapper arms of the first pair are electrically connected to place the electrical actuator and the first switch in series.

14. A manually enabled relay as in claim 13 wherein:

the electrically energized actuator means comprises an electrically heated bimetallic element positioned to lift the free end of said one arm of the first pair onto the latch when the bimetallic element is heated.

15. A manually enabled relay as in claim 14 wherein: the bimetallic element is positioned when not heated to hold the other clapper arm of the first pair out of contact with the one arm of the first pair in the latched position.

16. A manually enabled relay as in claim 11 wherein: the electrically energized actuator means comprises an electromagnetic solenoid engaging the clapper arms of the first and second pair.

17. A manually enabled relay as in claim 11 wherein: the manually operated actuator means has a first position relative to the movable latch permitting the latch to hold the one arm in a latched condition and a second position holding the latch and the one arm unlatched, and the manually operated actuator means in the second position engages and holds the respective clapper arms of the first and second pairs apart.

18. A manually enabled relay as in claim 17 wherein: the second switch formed by the second pair of clapper arms is electrically connected with the electrically energized actuating means.

19. A manually enabled relay as defined in claim 11 wherein:

the electrically energized actuator means is mechanically connected with the second switch to move one of the clapper arms of the switch onto the movable latch out of contact with the other clapper arm of the switch, and is electrically connected in series with the second switch.

20. A manually enabled relay as in claim 19 wherein: the manually operated actuator means includes a depressible plunger operatively engagable with the movable latch and with the first switch to hold the clapper arms apart when the plunger is depressed.

21. A manually set magnetic relay comprising:

first switch means having open and closed switch conditions; electromotive force generating means including a coil operatively connected to the first switch means for moving the first switch means between the switch conditions;

second switch means having open and closed switch conditions and serially coupled to the coil of the electromotive force generating means to permit energization and de-energization of the coil; latch means operatively engagable with said second switch means for holding the second switch means in the open and latched condition;

the electromotive force generating means also being operatively connected to the second switch means to move the second switch means to the open and latched condition; and f

manually operable actuator means for disengaging the second switch means and the latching means.

22. A manually set magnetic relay as in claim 21 wherein:

the latch means is also engagable with the first switch means for holding the first switch means in the open and latched condition.

23. A manually set magnetic relay as in claim 22 wherein:

the first switch means and the second switch means are each comprised of a pair of parallel and resilient clapper arms; and

the clapper arms of the second switch means assume the closed condition in the unlatched condition.
